UNITED STATES PATENT OFFICE.

LOUIS WOJIDKOW, OF BROOKLYN, NEW YORK.

DESIGN FOR A BREAD OR CAKE TRAY.

SPECIFICATION forming part of Design No. 27,935, dated December 7, 1897.

Application filed October 20, 1897. Serial No. 655,862. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for Bread or Cake Trays, of which the following is a specification, reference being had to the accompanying drawings, forming a part thereof.

10 Figure 1 is a plan view of a bread or cake tray, showing my new design. Fig. 2 is a central longitudinal section. Fig. 3 is a central transverse section.

As shown in the drawings, the leading or 15 material feature of my design consists of a series of radiating falciform or horn-shaped elevations extending along the surface of the rim.

The body of the tray has a flattened bottom 20 *a* and a flaring rim *A*, the upper part of said rim being provided with scallops *b*, which are edged by means of a beaded border *b'*. At

the ends of the tray are formed beaded loops *C C'*.

Radiating from a point near the bottom *a*, 25 so as to extend toward the outer edge of the tray, are ornamental side figures composed of several series of falciform elevations *d*, which are convexed and which are spread outwardly or flare in opposite directions away from the 30 mid-length of the tray, so that the points thereof extend toward the ends of the tray.

Having described my invention, what I claim as new, and desire to secure by Letters Patent, is—

35 A design for a bread or cake tray, substantially as herein shown and described.

In testimony that I claim the foregoing as my invention I have signed my name in presence of two subscribing witnesses.

LOUIS WOJIDKOW.
